UNITED STATES PATENT OFFICE.

GEORGE A. CLARK, OF LOWELL, MASSACHUSETTS, ASSIGNOR TO THE DRAPER COMPANY, OF PORTLAND, MAINE, AND HOPEDALE, MASSACHUSETTS.

BOBBIN-HOLDER.

SPECIFICATION forming part of Letters Patent No. 645,417, dated March 13, 1900.

Application filed December 11, 1899. Serial No. 739,891. (No model.)

To all whom it may concern:

Be it known that I, GEORGE A. CLARK, a citizen of the United States, and a resident of Lowell, county of Middlesex, and State of Massachusetts, have invented an Improvement in Bobbin-Holders, of which the following description, in connection with the accompanying drawings, is a specification, like letters on the drawings representing like parts.

This invention has for its object the production of a novel bobbin-holder constructed and arranged to support a bobbin during the unwinding of the yarn therefrom and to permit the discharge of the spent or empty bobbin in a convenient and rapid manner.

The operation of inserting a new bobbin by the attendant effects the ejection or discharge of the spent bobbin without handling the latter at all, while heretofore the attendant has been obliged to reach in and pick the spent bobbin out of the holder and then toss it into a box or down a chute.

By means of this invention the spent bobbin is ejected from the rear of the bobbin-holder as the fresh bobbin is inserted, the ejected bobbin falling into a chute or other device suitably attached to the spooler to direct the bobbin to a box or other convenient or desirable collecting device, saving much hand labor and facilitating the operation of the apparatus.

Figure 1 is a cross-sectional view of a portion of a spooling-machine, showing a bobbin-holder embodying one form of my invention with a discharge-chute and receptacle for spent bobbins. Fig. 2 is an enlarged side elevation of one of the bobbin-holders with a full bobbin therein. Fig. 3 is a rear end elevation of the bobbin-holder, showing the closure or gate for the discharge-opening in normal position; and Fig. 4 is a similar view showing the gate open to permit the exit of a spent bobbin.

Referring to Fig. 1, the frame A⁸, driving-drum A¹⁰ for the spindles a, on which are mounted the spools A² to receive the thread from the bobbins, the rod B, upon which the bobbin-holders are secured, and the thread-

guides t may be and are all of well-known or usual construction.

Referring more particularly to Figs. 2, 3, and 4, the holder is shown as comprising, essentially, an upturned overhanging arm A, having at its lower end a clamp A', provided with a set-screw, a bracket b extended from the clamp having attached thereto a rest or pan d for the bobbin C, all substantially as in United States Patent No. 575,929, granted January 26, 1897, swinging guards g being supported on the forwardly-extended part of the arm A. I have herein shown the laterally-enlarged upright portion A^X of the arm at the rear of the rest d and which forms a back-stop for the bobbin as cut away to form a discharge-opening a^X, through which a spent bobbin is ejected.

As shown in Fig. 2, the bobbin-head c is maintained out-of-alignment with the opening a^X by the yarn wound upon the bobbin; but as the yarn is unwound the bobbin comes nearer and nearer to the pan d and the spent or substantially-empty bobbin will be in position to pass through said opening.

In order to prevent the premature discharge of the bobbin, I provide a closure or gate m for the opening, pivotally mounted by a pin m' in ears a¹⁰ on the rear of the back-stop at one side of the opening a^X, an arm m² extended substantially at right angles to the gate having its end enlarged or weighted, as at m³. As shown, the fulcrum m' is oblique or inclined to the vertical, so that the weighted arm, heavier than the gate, will operate to shut the latter and normally close the opening, the weight of the bobbin being insufficient of itself to open the gate. Now supposing the bobbin has been unwound it is in proper position to be ejected, and the operative simply puts the fresh bobbin in from the front, its head butting against the tip of the empty one and pushing it through the opening, the gate m being swung to one side by the spent bobbin. As soon as the latter is ejected the gate swings shut, while the head of the fresh bobbin engages the face of the back-stop out of alignment with the discharge-opening. The operative is thus relieved of

one hand operation which now consumes considerable time, amounting to a great deal in the aggregate, as several thousand may have to be handled in the course of a day.

5 I have shown in Fig. 1 a trough or chute L, with its upper end beneath the discharge-openings of the several bobbin-holders, so that the ejected bobbins fall into the chute and are directed to a box L^x or other convenient receptacle for collecting them. The closing movement of the gate is stopped by engagement of a part thereof with the back-stop adjacent the fulcrum, as at a²⁰, Fig. 3.

15 My invention is not restricted to the precise construction and arrangement shown, as the same may be modified or rearranged in various particulars without departing from the spirit and scope of my invention.

Having described my invention, what I 20 claim as new, and desire to secure by Letters Patent, is—

1. In a bobbin-holder, a rest for the bobbin, and a back-stop having a discharge-opening for a spent bobbin, the unwound bobbin being 25 maintained by the yarn thereupon out of alinement with the opening.

2. In a bobbin-holder, a rest for the bobbin, a back-stop having a discharge-opening for a spent bobbin, the yarn maintaining a bobbin 30 out of alinement with the opening till unwound, and a movable closure for the opening.

3. In a bobbin-holder, a rest for the bobbin, an upturned, overhanging arm forming a 35 back-stop at the rear of the rest and provided with a discharge-opening for a spent bobbin, the unwound bobbin being maintained by the yarn thereupon out of alinement with the opening, and a swinging gate to normally 40 close said discharge-opening.

4. In a bobbin-holder, a rest for the bobbin, a back-stop having a discharge-opening for a spent bobbin, the yarn maintaining a bobbin 45 out of alinement with the opening till unwound, and a pivotally-mounted, normally-closed gate for said opening.

5. In a bobbin-holder, a rest or pan, and

an upturned back-stop at the rear end thereof having a discharge-opening to permit the passage therethrough of a spent bobbin, the 50 upper edge of the opening extending across the path of an unwound bobbin and preventing its discharge.

6. In a bobbin-holder, a bracket, a rest or pan for the bobbin, and an upturned back-stop, both mounted on the bracket, said back-stop having a discharge-opening therein, the 55 yarn on a bobbin maintaining it out of alinement with the said opening.

7. In a bobbin-holder, a rest for the bobbin, 60 a back-stop having a discharge-opening at the rear end of the rest, and a self-shutting gate to normally close said opening.

8. In a bobbin-holder, a rest for the bobbin, 65 an upturned back-stop at the rear end thereof having a discharge-opening for a spent bobbin, a gate obliquely fulcrumed adjacent and to close the opening, and a weighted arm on the gate, to normally maintain the latter shut.

9. A spooling-machine having a series of 70 bobbin-holders each provided with a bobbin-rest and a back-stop having a discharge-opening for a spent bobbin, and a chute located below the bobbin-holders and having its open top arranged to receive spent bobbins when 75 ejected through the discharge-openings of the holders.

10. A bobbin-holder having a rest for the bobbin, and means to permit ejection of the spent bobbin when moved longitudinally upon 80 the rest toward the back of the latter.

11. A bobbin-holder having a rest for the bobbin, a discharge-outlet for the passage of the spent bobbin when engaged and moved longitudinally by an incoming fresh bobbin, 85 and means to prevent accidental ejection of a bobbin.

In testimony whereof I have signed my name to this specification in the presence of two subscribing witnesses.

GEORGE A. CLARK.
